BED SHEET TIGHTENER

Nellie L. Reid, 330 Auburn Road W., Rochester, Mich.

Filed Nov. 17, 1961, Ser. No. 67,583

Term of patent 14 years

(Cl. D17—3)

FIGURE 1 is a top view of a bed sheet tightener embodying my new design;

FIGURE 2 is an edge view;

FIGURE 3 is a cross sectional view as taken along line 3—3 of FIGURE 1 looking in the direction of the arrows;

FIGURE 4 is a cross sectional view as taken along the line 4—4 of FIGURE 1 looking in the direction of the arrows.

FIGURE 5 is a longitudinal center sectional view as taken along line 5—5 of FIGURE 1, looking in the direction of the arrows.

I claim:

The ornamental design for a bed sheet tightener, substantially as shown.
